SHOE STIFFENER BLANK AND METHOD OF
MAKING THE SAMEStanley P. Lovell, Newton Center, Mass., assignor
to Beckwith Manufacturing Company, Dover,
N. H., a corporation of Massachusetts

Application May 26, 1937, Serial No. 144,843

13 Claims. (Cl. 12—146)

The present invention relates to shoe stiffener blanks and method of making the same, and more particularly to that type of blank of the pre-stiffened type which is cut or died out from a sheet of stiffened material, such, for example, as a felt saturated with thermoplastic stiffening compound.

Heretofore these blanks have been died out one at a time by means of a hand die, prior attempts to cut these blanks with a multiple die having proved unsuccessful in commercial practice, due to the great length of cutting edge required by the conventional or standard outline or configuration of the blank per square unit of surface, and the consequent excessive pressure needed to force such a die through the material.

While these stiffener blanks may be successfully died out with the single unit die, this operation is necessarily slow and laborious and involves a great waste of material because, due to the brittleness of the stiffening compound, one or more cracks would ordinarily be formed, extending outwardly from the line of cut of the die into the uncut material. To avoid such cracks in blanks cut from adjacent portions of the sheet material it was necessary to space the cutting die a sufficient distance to exclude them, resulting in the formation of a border or zone of stiffener material which was of substantial width and extended entirely around the blanks. This border or zone was all waste and represented a very large proportion, sometimes as high as 24%, of area of the original sheet.

It has been attempted to avoid the formation of these cracks with the consequent high wastage by dieing out the blanks with a multiple unit die when the sheet material is soft and pliant from heat, as disclosed in my prior Patent No. 1,962,603 of June 12, 1934, and while this enabled the blanks to be cut close to one another from the sheet without forming cracks, thus eliminating a large part of the waste, nevertheless difficulty was experienced in keeping the cutting edges of the die clean and free from the sticky, gummy, material with which the blank was stiffened and which interfered not only with the cutting operation itself, but caused a serious variation in the size of the blanks cut by the same size die.

Another objection to the present method of producing stiffener blanks by the use of a single unit cutting die is the amount of hand labor required in handling the cut out blanks preparatory to the skiving operation. This operation is ordinarily performed in a machine having a magazine and automatic feed, the cut blanks be-

ing stacked by hand in the magazine in a certain definite angular alignment. Where these blanks are cut by a single die, each blank has to be picked up by itself, brought to the proper alignment and stacked preparatory to being transferred to the magazine of the skiving machine.

The present invention seeks to avoid these objections and disadvantages of these prior methods of manufacture, and to produce stiffener blanks from sheets of stiffening material at much higher speeds of production, with much less wastage, and with the cut blanks aligned in piles or stacks ready for transfer to the skiving or other machine for further manipulation.

To the above ends the present invention contemplates the forming of the stiffener blanks with their side edges straight for substantial portions of the distance from the vamp line to the toe or tip, instead of convexly curved, as is the present practice. By having the straight portions of adjacent blanks coincide, a single cutting edge will serve for both blanks. As a result, the total length of the cutting edges of a multiple unit die for cutting the new form of blank will be sufficiently reduced over one having a complete and independent cutting edge for the entire perimeter of each blank, as required with the shape of blank now in commercial use, that the pressure required per unit of area for operating such new die member will be much less and well within the practical limits.

Furthermore, when cutting a sheet of material with a multiple die in a single operation, the sheet will be left sufficiently coherent to permit handling and stacking as a unit, yet with the stiffener blanks and the waste pieces sufficiently severed from the sheet to permit separation therefrom, and from one another, with a minimum of effort.

Thus the operator, after stacking the sheets in vertical alignment, is enabled to remove the blanks a pile or stack at a time, all similarly aligned, and transfer them to the magazine of the skiving machine or other instrumentality. The handling of each individual blank by itself is thus avoided, the blanks first being handled in a horizontal group or layer in the original sheet from which they are formed, and later in vertical aligned stacks consisting of one blank from each of the sheets.

In the accompanying drawing which illustrates one embodiment of the present invention, Fig. 1 is a top plan view showing, in full line, the shape or contour of the stiffener blank when formed in

- accordance with the present invention, those portions of the old blank, which have been altered or changed in the new construction, being shown in dotted line; Fig. 2 is a top plan view, 5 on a reduced scale, of a portion of a sheet of material showing the arrangement or interlock of the improved stiffener blanks after they have been cut but before they have been separated from the sheet; and Fig. 3 is a perspective view 10 of a corner portion of a vertical pile of cut sheets showing the manner in which the stacks of aligned blanks and waste pieces are formed and how each stack may be separated from the pile of sheets and handled as a unit.
- 15 The new and improved stiffener blank consists of a generally segmental-shaped piece of felt or other suitable material saturated with a stiffener compound, such as one of the well known thermoplastics, comprising asphalt, resin, wax and other 20 materials. The stiffening material for the blanks is usually produced by passing the felt or other base material through a body of the hot stiffener compound, the excess being removed by pressure rolls, and the sheet or web allowed to cool and 25 stiffen. When cold and stiff the blank of the shape shown in Fig. 1 is died therefrom.

As heretofore formed, these blanks 4 had a rounded toe or tip portion 6 and a vamp line or edge 8, shown in the drawing as straight, but 30 sometimes either convex or concave. The side margins or edges were convexly curved from the corner portions 10 through the intermediate portions 12, shown in dotted line, to the toe portion 6.

As constructed in accordance with the present 35 invention, this intermediate side portion, instead of being convexly curved as shown at 12, is formed in a straight line 14, shown in full lines. This permits the blanks to be cut from a sheet of stiffener material in the manner illustrated in 40 Fig. 2, with the straight portions of the sides of adjacent reversely arranged blanks coinciding for substantial distances so that there is a single line of severance between such blanks. With the blanks positioned in this manner on the sheet of 45 stiffener material, the wastage, except at certain of the side margins, consists only of the small triangular pieces 16 left between the curved toe 6 of one blank, the straight vamp line of another, and the curved corner portion 10 of the third of 50 three contiguous blanks.

A comparison of these small areas with the substantial amount of border or zone required to be left completely around the blank as heretofore formed and as illustrated in Fig. 3 of my 55 prior patent, shows the great saving effected by the present invention. By actual measurement it has been found that this waste of material could be reduced from as high as twenty-two per cent of the original sheet to as low as four per cent, representing a net saving of eighteen per 60 cent in the cost of the stiffener material, which has little if any value as waste.

After the box toe is cut from the sheet of stiffener material it is ordinarily skived, as at 18, 65 along the vamp line 8 to form a thin or feather edge which will merge into the vamp and lining in the shoe without leaving any distinctive line or ridge showing on the top of the vamp. To facilitate the handling of the cut blanks and transfer them to the magazine of the automatic skiving machine in the proper position or alignment, the sheets of material 20 as they come from the die press are piled vertically, one above the other, in the same angular position they occupied in the 70 press so that vertical stacks or piles of blanks will

be formed with all the blanks in the same stack facing the same way, but different stacks facing different ways. Such stacks are indicated in Fig. 3 of the drawing at 22, 24 and 26, and the waste material at 28. Ordinarily the sheets as they are 5 discharged from the die press maintain their sheet formation because of the character of the material from which they are formed, so that they may be piled vertically, one above another, as shown.

From such a pile the operator can remove the stacks of waste material and the blanks as units, and with little effort. Thus, after removing the stack of waste material corresponding to that indicated at 28 in Fig. 3, which happens to be much 15 larger than most of the waste stacks because of its location at the side edge of the pile of sheets, the operator grasps the stack of blanks indicated at 22, separates them from the rest of the sheets, and then transfers them, as a unit, to the magazine 20 of the skiving machine, or to some intermediate point.

Similarly, the other stacks of waste material will be removed and the other stacks of blanks, such as 24 and 26, transferred as units with such 25 angular adjustment as may be required to bring them into proper alignment in the magazine or other holder.

In actual practice it has been found that a satisfactory size of multiple die and sheet may consist of thirty-six units or stiffener blanks and 30 that a pile of cut sheets sixty-five units high is a convenient size for handling.

The improved form of stiffener blank is incorporated in the shoe in exactly the same manner 35 as with the blank now commonly used, being softened in an appropriate manner, as by heat if a thermoplastic stiffening compound is employed, or by a solvent if a solvent stiffening material is used, and then assembled in the regular 40 manner with the vamp, lining, and other shoe parts, and pulled over the last and lasted in place.

With the prior form of stiffener this operation invariably resulted in the formation of flutes or ears of surplus stiffener blank material adjacent 45 to and on each side of the toe or tip. This surplus material, formed between the side jaws and the end jaw on the pulling over machine, would either be trimmed off and thrown away or forced down upon the bottom of the last. Its disposal, 50 in one way or another, has always been a problem.

With the new form of stiffener blank, however, owing to the formation of this intermediate portion of the side edges of the blank in straight lines instead of convex curves, this fullness or 55 surplus of the box toe material disappears, and the ears or flutes consist only of the upper leather and lining, the box toe curving downwardly to form a side wall with an adequate flange.

Thus, the improved form of stiffener blank not 60 only can be produced at a minimum of cost for labor and material, but also facilitates and improves the lasting operation.

Having thus described the invention, what is claimed is:

1. A pre-stiffened blank for box toes comprising a piece of suitable material impregnated with stiffening compound and being of generally segmental shape having a convexly curved toe portion, convexly curving corner side portions adjacent the vamp line, and straight side portions intermediate the toe and the corner side portions.
2. A pre-stiffened blank for box toes comprising a piece of suitable material impregnated with

65

70

75

stiffening compound and being of generally segmental shape with a straight vamp line, a convexly curved toe portion, and substantial lengths of straight side portions oppositely inclined at the same angle to the vamp line.

5. 3. The method of making stiffener blanks for box toes which consists in cutting a sheet of pre-stiffened material in a single operation into a plurality of blanks having their toe portions curved and their side edges straight for a substantial length, adjacent blanks having their straight side edges contiguous.

10. 4. The method of making stiffener blanks for box toes which consists in cutting a sheet of pre-stiffened material in a single operation into a plurality of blanks having their toe portions curved and their side edges straight for a substantial length, adjacent blanks having their straight edges contiguous and their vamp lines oppositely disposed.

15. 5. The method of cutting stiffener blanks with curved toe portions from a sheet of pre-stiffened material which consists in severing the blanks along lines to form in a single operation a plurality of parallel rows of blanks, the blanks of each row being oppositely positioned, with respect to the vamp line, from the blanks in adjacent rows, and the side edges of adjacent blanks in the adjacent rows being straight and contiguous for substantial lengths.

20. 6. The method of cutting stiffener blanks with curved toe portions from a sheet of pre-stiffened material which consists in severing the blanks along lines to form two series of parallel rows of blanks, the two series being at right angles to one another, the adjacent blanks in one series of rows being aligned with the top of one blank toward the vamp line of the adjacent blank, and adjacent blanks in the other series of rows having their vamp lines oppositely disposed and their side edges straight and contiguous for a substantial distance.

25. 7. The method of making stiffener blanks for box toes which consists in successively and similarly cutting a multiplicity of blanks from sheets of material, superposing the cut sheets on one another while maintaining the sheets intact to form a pile with the corresponding parts in vertical alignment, and removing, as a unit, vertical stacks of aligned blanks.

30. 8. The method of making stiffener blanks for box toes which consists in successively and similarly cutting a multiplicity of blanks and waste pieces from a series of sheets of stiffening material, stacking the cut sheets in vertical piles

while maintaining the sheets intact with similar parts in alignment, and transferring, as a unit, the stacks of aligned blanks from the pile of sheets to a skiving machine magazine.

5. 9. The method of manufacturing irregular shaped articles from sheet material which consists in successively and similarly cutting sheets of material into pluralities of the articles, handling as a unit in sheet form a plurality of the cut articles formed from the same sheet, and thereafter handling as a unit a vertical stack of similar articles, each from a different sheet of material.

10. 10. The step in the method of making shoe stiffener blanks which consists in cutting a sheet of material in one operation into a plurality of blanks with a portion of their side edges straight for a substantial length and another portion curved, adjacent blanks being oppositely disposed and having their straight edges contiguous.

15. 11. A pre-stiffened blank for box toes comprising a piece of suitable material impregnated with stiffening compound and being of generally segmental shape, with a straight vamp line, convexly curved corner portions adjacent the vamp line, a convexly curved toe portion, and straight side portions intermediate the curved toe and corner portions.

20. 12. The method of cutting stiffener blanks with curved toe portions from a sheet of pre-stiffened material which consists in severing the blanks along lines to form two series of parallel rows of blanks, the two series being at right angles to one another, the adjacent blanks in one series of rows being aligned with the top of one blank toward the vamp line of the adjacent blank, and adjacent blanks in the other series of rows having their vamp lines oppositely disposed and their side edges straight and contiguous for a substantial distance, and the end portions of their vamp lines straight and contiguous to similar portions of the vamp lines of adjacent blanks in adjacent rows of such other series.

25. 13. The method of cutting from a sheet of pre-stiffened material a stiffener blank having a curved toe portion, a straight vamp line and substantial lengths of straight side edges between the toe portion and the vamp line, which consists in cutting the vamp line with its end portions coincident with the end portions of the vamp lines of certain adjacent blanks and with the straight side edges coincident with straight side edges of other adjacent blanks.
